Inventor:

UNITED STATES PATENT OFFICE.

FREDERIC W. RITTER, JR., OF WASHINGTON, DISTRICT OF COLUMBIA, ASSIGNOR TO OIL WELL SUPPLY COMPANY, OF PITTSBURG, PENNSYLVANIA, A CORPORATION OF PENNSYLVANIA.

UNDERREAMER.

No. 926,608.

Specification of Letters Patent. Patented June 29, 1909.

Application filed June 22, 1908. Serial No. 439,833.

To all whom it may concern:

Be it known that I, FREDERIC W. RITTER, Jr., a citizen of the United States, residing at Washington city, in the District of Columbia, have invented certain new and useful Improvements in Underreamers; and I do hereby declare the following to be a full, clear, and exact description of the invention, such as will enable others skilled in the art 10 to which it appertains to make and use the same.

My invention relates to the construction of that class of devices commonly termed underreamers having for their purpose the 15 enlargement of the diameter of Artesian or like wells where casing is required and the drilling is done through the casing. In this class of devices, it is essential that the reaming bits be collapsible and expandable in order that the tool may be inserted and withdrawn through the casing, and it is also desirable that the combination of stock and bits should be such that the force of the blow is transmitted to the stock on lines 20 substantially parallel to its axis, that any tendency of the bits to spread beyond the normal be restrained or counteracted, and that solid abutments on the stock for the bits be provided. To effect these several 25 objects I combine with a stock having abutments and a distance-block located intermediate of said abutments a bit support, bits slidably supported so as to be laterally and bodily movable on said bit support, said 30 bits being slidably connected with the stock so as to be limited as to their lateral movement, and resilient means interposed between the bits and supported upon the distance-block whereby the bits are normally 35 held in a spread position and in contact with the abutments of the stock.

A second feature of my invention embraces the combination with a stock having abutments and a distance-block, of a bit support, sliding bits movable bodily upon the bit support, and a spring located between the bits and supported upon the distance-block, of means for maintaining the relation of the spring to the distance-block 40 and the bit support.

A third feature of my invention embraces the combination with a stock having abutments and a distance block, of a bit support, sliding bits movable bodily upon the bit 45 support, and a spring located between the

sliding bits and supported on the distance-block, of means for preventing the displacement of the bit support.

There are other, minor, features of invention, embracing particular combinations 60 and features of elemental construction, all as will hereinafter more fully appear.

In the drawings chosen for the purpose of illustrating my invention, the scope whereof is pointed out in the claims, Figure 1 is a 65 view partly in section and partly in elevation, of the lower end of the stock and the bits, of an underreamer embodying my invention. Fig. 2 is a view in elevation of the lower end of the stock and bits of an un- 70 derreamer embodying my invention. Fig. 3 is a transverse section thereof taken on the line 3—3, Fig. 2. Fig. 4 is an elevation of the lower end of the stock and bits shown, at right angles to the view in Fig. 2. Fig. 5 a 75 vertical central section of the lower end of a stock and bits constituting a modification of the underreamer shown in Figs. 1 to 4 inclusive. Fig. 6 is a view in elevation of the lower end of the stock and bits of the modified 80 form of underreamer shown in Fig. 5. Fig. 7 is a similar view to Fig. 6 taken at right angles thereto, and Fig. 8 is a cross sectional view of the modified form of underreamer taken on line 8—8, Fig. 5. 85

Like symbols refer to like parts wherever they occur.

I will now proceed to describe my invention more fully so that others skilled in the art to which it appertains may apply the 90 same.

In the drawings, A indicates the stock, B, B the bits, and C the bit support of an underreamer.

The stock A is provided at its opposite 95 sides with bit recesses a, a for the reception of the tangs b, b of the bits B, B. These bit recesses a, a are closed above by flat walls or abutments a', a' against which the flat upper ends b' of the bit tangs abut when the bits 100 are expanded or in their normal operative position. On either side of the said recesses a, a at the lower end of stock A are other flat abutments a'', a'' against which flat shoulders b'', b'' on either side of the tangs b of the 105 bits also abut when the bits are in operative position. The lateral walls of the bit-recesses a, a are channeled longitudinally of the stock to form ways a³ for the reception of lateral projections b³, b³ on the bit tangs b, and 110

said channels have an inward and upward inclination, or narrow from below upward to cause and maintain the expansion of the bits when in their operative or normal position.

5 At the lower end of the stock A and located intermediate of the abutments a^2 , a^2 , is a distance-block D with which the inner faces of the bits B, B engage, and which serves to maintain the bits expanded when the bits are 10 in their highest position or fully seated on the abutments of the stock.

The stock A may have a central bore a^4 which extends from the upper end thereof down into the distance-block D forming on 15 the upper face of said distance-block a cup or chamber, d for confining the compression spring E, which cup or chamber d is slotted vertically as at d' to permit of the transverse passage and vertical movement of the bit- 20 support C.

The bits B are provided with tangs b the upper ends b' of which are flat to engage the flat abutments a' of the stock. Lower down, the bits have flat shoulders b^2 , b^2 to engage 25 the flat abutments a^2 , a^2 at the lower end of the stock A. Projecting laterally from the tangs b are the ribs or projections b^3 , b^3 which enter the channels or ways a^3 in the lateral walls of the bit recesses a , a , and this construction permits of a longitudinal sliding movement of the bits with some lateral play of the bits bodily on the bit support C, yet so 30 confines the bits to the stock that no abnormal spreading of the bits can occur. It will 35 thus be seen that the sliding connection between the stock and bits in Figs. 1 to 4 of the drawings is in the character of a dove-tail connection which permits of some bodily lateral movement of the bits. The tangs of the 40 bits B are also provided with slots b^4 by means of which they are movably supported on a cross-bar or yoke C, and are recessed on their inner faces, as at b^5 to accommodate or 45 include the distance-block, when the bits are drawn down to their lowest position, or collapsed, as indicated in dotted lines, Figs. 1 and 2 of the drawings. The formation of the recesses b^5 of the bits and the undersurface of the distance-block D should be of such a 50 character as will facilitate the disengagement of the bits from the distance-block under the lifting force of compression spring E.

C indicates a bit support of such proportions as will pass through the elongated slot d' of the spring cup d and on which the bits B, B are suspended, or supported, so as to be capable of rocking and of moving bodily to and from each other. This bit-support 55 may be of any desired form, but in the preferred form shown in Figs. 1, 3 and 4 of the drawings, it is in the form of a narrow bar having a depression c' upon its lower edge, and centrally located, for the reception of a disk c which rests upon the compression 60 spring E within the cup or chamber d , and

this prevents any endwise displacement of the support C.

In the modified construction shown in Figs. 5 to 8 inclusive, of the drawings, in lieu of utilizing the channels or ways a^3 and lateral projections b^3 for forming the sliding connection between the stock and bits, the stock A is provided with a socket S having a slight inward taper for the reception and guidance of the upper ends of the tangs b of the bits, and this socket has a flat bottom so as to form flat abutments for the upper ends of the tangs b of bits B. The shoulders of the bit are upwardly and inwardly inclined as at s to engage abutments of like inclination on the lower end of the stock A. It will be noted that the coaction of the socket S and the upwardly and inwardly inclined abutments at the lower end of the stock, with the upper and confined ends of the tangs b and the inclined shoulders s of the bits in Figs. 5 to 8 of the drawing, is in effect the same as the coaction of the channels a^3 of the stock and the lateral ribs b^3 of the bit tangs, in Figs. 1 to 4 of the drawings, that is to say, 85 the coaction of the combining elements in both instances confines the bits to the stock while permitting the restricted bodily lateral movement of the bits required for the expansion and collapse of the bits, and at the same 90 time insures the solid abutment of the bits on the stock when the bits are in the normal or operative position as shown in the full lines of the drawings.

In the modified construction shown in Figs. 5 to 8 of the drawings, in lieu of the cup or chamber d on the upper face of distance-block D for confining spring E and maintaining the relation of the spring to the distance block and bit support C, there may be employed a guide rod R inserted from below through an opening in the distance-block D and fastened thereto by a pin r or in other suitable manner, its upper end entering a recess r' in the bottom of socket S. This rod passes through the compression spring E and also through an opening in the bit support C, and thus serves effectively to confine the spring E and prevent any endwise movement or displacement of the bit support C. 110

In assembling the elements of the underreamer when the preferred construction of the general character shown in Figs. 1 to 4 of the drawing is adopted, the compression spring E is passed down through central bore a^4 of the stock to its position in cup d , and the disk c dropped into position on the upper end of said spring. Next, the tangs b of the bits are passed up into the bit recesses 125 in the lower end of the stock with the lateral ribs or projections b^3 of the bit tangs in the ways a^3 of the stock until the abutments of the stock and bits meet, as indicated in the full lines of the drawings, after which the 130

spring E is placed under compression, which can be readily done through the bore a^4 of the stock. Finally, the bit-support C is passed transversely through the slots b^4 in the tangs b of the bits and through the elongated slot d' in the walls of the spring chamber d, whereupon, upon the removal of pressure from spring E the disk e will seat itself in the recess c' on the lower edge of the bit support C and confine the bit support against endwise displacement.

In case of the modified construction shown in Figs. 5 to 8 of the drawing, in assembling the parts, one bit B and the bit support C are first placed in position as indicated in the full lines of the drawing after which the compression spring is placed in position between the upper surface of the distance-block D and the under surface of bit support C. Next, the bit-support is drawn down by the attached bit until it reaches the position indicated in dotted lines which will bring the bit-support below the mouth of socket S, whereupon the other bit is hung on the bit support and when the pressure is removed from spring E the tangs b , b of both bits will be forced up into socket S and at the same time the inclined shoulders s on the bits will engage the inclined abutments on the lower end of the stock A. Finally, the rod R will be passed through the opening in the distance-block D, springs E and bit-support C and will be secured thereon by the pin r, or in other suitable manner.

The construction being substantially such as hereinbefore set forth, when the underreamer is to be introduced through the casing the bits B, B are drawn down until the recesses b^5 on their inner faces are opposite the lower end of the distance-block D when the bits can be forced toward each other into the collapsed position shown in dotted lines. This puts the spring E under compression, in which condition it remains during the passage of the underreamer through the casing, the bits being retained in said position by the walls of the casing. When the bits emerge from the lower end of the casing the pressure on spring E is relaxed whereupon the reaction of the spring forces the bits upward until they are seated solidly upon the abutments of the stock, the distance-block D separating the lower portions of the bits and thereafter maintaining them in their normal or operative position while the ways a^3 and ribs b^3 in the one instance, and the socket S and the inclined abutments and shoulders s in the other instance counteract any excessive spreading or lateral movement of the bits.

When withdrawing the underreamer from the casing the projecting outer faces of the tangs b , b of the bits first encounter the lower end of the casing and the bits are held there-by while the stock A continues to rise, the

compression of the spring E permitting this relative longitudinal movement of the bits and stock until such time as the recesses b^5 on the inner faces of the bits are opposite the under face of the distance-block D, 70 whereupon the bits collapse or assume the position shown in dotted lines, thus permitting the under reamer to be drawn into and through the casing.

One advantage derived from the location 75 of the spring on the distance block and between the bits is that the bit stock or mandrel may be materially shortened thus bringing the jars nearer to the bits and rendering the tool more effective. Another advantage 80 is the securing of a more solid bit-stock for the better transmission of the blow and the support of the bits near their cutting faces.

Having thus described my invention, what I claim and desire to secure by Letters Pat- 85 ent is:

1. In an underreamer, the combination with a bit-stock having laterally disposed abutments at its lower end and a distance-block intermediate of said abutments, of a 90 bit-support, bits carried by the bit-support and bodily movable thereon, said bits being slidingly connected to the bit-stock so as to have a limited lateral movement and being adapted to engage said abutments near the 95 lower ends of said bits, and a resilient element interposed between the bits and supported on the distance block for holding the bits normally expanded and in contact with the abutments of the bit-stock. 100

2. In an underreamer, the combination with a bit-stock having laterally disposed abutments at its lower end and a distance-block intermediate of said abutments, of a bit support, bits slidingly connected with the 105 bit-stock and bodily movable on the bit-support, a spring located between the bits and supported on the distance-block for holding the bits normally expanded and in contact near their lower ends with the abutments of 110 the bit-stock, and means connected to the distance block for maintaining the spring in alinement with the distance-block and bit-support.

3. In an underreamer, the combination 115 with a bit-stock having lateral abutments at its lower end, a distance-block intermediate of said abutments, and an axial bore which terminates at the distance-block and forms a spring chamber the walls of which are slotted 120 transversely for the passage of a bit support, of a bit-support, bits slidingly connected with the bit-stock, and a spring located in the bore of the stock between the bits and supported by the distance-block for holding 125 the bits normally expanded and in contact near their lower ends with the abutments of the bit-stock.

4. In an underreamer, the combination 130 with a bit-stock having lateral abutments

- and a distance-block, said bit-stock provided with an axial bore and a transverse bit-support slot, of a bit-support, bits carried by the bit-support and slidingly connected with the bit-stock, a spring located between the bits and supported on the distance-block for holding the bits normally expanded and in contact with the abutments of the bit-stock, and means within the axial bore of the bit-stock, 5 confined thereby and which engages the bit-support for preventing the endwise displacement of the bit-support, said means interposed between the spring and the bit-support.
- 10 5. In an underreamer, the combination with a bit-stock having an axial bore, lateral abutments, and a transverse slot for the passage of a bit-support, of a bit-support, a disk confined within the axial bore of the bit- 20 stock and which engages the bit-support to prevent its endwise displacement, bits carried by the bit-support and slidingly connected with the bit-stock, and a spring located between the bits and beneath the bit- 25 support for holding the bits normally expanded and in contact with the abutments of the bit-stock.
6. In an underreamer, the combination with a bit-stock having lateral abutments 30 and an axial bore and provided with a trans- 35 verse slot for the passage of a bit-support, of a bit-support having a recess in its edge for the reception of a disk, bits carried by the bit-support, a compression spring located in the bore of the bit-stock between the bits and beneath the bit-support for holding the bits

normally expanded and in contact with the abutments of the bit-stock, and a disk confined in the axial bore of the bit-stock between the spring and bit-support and which 40 engages in the recess of the bit-support.

7. A bit-stock for underreamers, said bit stock having lateral bit-abutments which are adapted to engage cutting bits near the lower ends of the latter and a distance-block 45 intermediate of said abutments, and provided with an axial bore which extends down from the upper end of said stock and terminates at the distance-block constituting a spring chamber intermediate of said bit- 50 abutments.

8. In an underreamer, the combination with a bit-stock having lateral abutments, a distance-block intermediate of said abutments and an axial bore which extends 55 downward to the distance block forming a spring chamber the walls of which are transversely slotted, of a bit-support, bits loosely carried by said bit-support and slidingly connected to the bit-stock, and a compression 60 spring located between the bits and interposed between the bit-support and distance-block for maintaining the bits normally in expanded position and in engagement near their lower ends with the abutments of the 65 bit-stock.

In testimony whereof I affix my signature, in presence of two subscribing witnesses.
